UNITED STATES PATENT OFFICE.

CLARENCE B. FOWLER, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,356,704.

Specification of Letters Patent. Patented Oct. 26, 1920.

Application filed January 27, 1919. Serial No. 273,207.

To all whom it may concern:

Be it known that I, CLARENCE B. FOWLER, a citizen of the United States, residing at New York, in the county of New York, 5 State of New York, have invented certain new and useful Improvements in Telephone-Exchange Systems, of which the following is a full, clear, concise, and exact description.

10 This invention relates to telephone exchange systems and more particularly to such systems in which connections are to be established between telephone lines terminating at a manual exchange and telephone 15 lines terminating at an automatic exchange.

It is frequently the practice in such systems to employ trunk circuits interconnecting the exchanges over which the operator at the manual exchange, in response to a 20 call received over a calling line terminating thereat, may select the desired line terminating at the automatic exchange.

In systems of this nature, it is desirable to eliminate any possibility of interference 25 resulting from any tones which may be transmitted to the operator at the manual exchange during such process.

It is the object of this invention to provide an improved system of this nature wherein 30 the operator's telephone set, although normally operatively associated with the trunk circuit upon the connection of the associated link circuit with the trunk, is effectively excluded therefrom during the calling 35 operation or during the association of the telephone set with another link circuit.

To attain these objects in accordance with one feature of the invention, means is provided associated with the link circuit employed 40 for selecting the desired line over the trunk, which means is responsive to the actuation of the calling or impulse-sending device to effectively exclude the operator's telephone set from association with such link 45 circuit.

In accordance with a second feature of the invention, means is provided associated with the above mentioned link circuit responsive to the connection of the operator's telephone 50 set to another link circuit for disconnecting the set from the first mentioned link circuit.

These and other features not specifically mentioned above will clearly appear from 55 the following specification and the annexed

drawing, in which the figure shows diagrammatically one embodiment of the invention as applied to link circuits at a manual exchange adapted for selecting over a trunk circuit a subscriber's line terminating at an 60 automatic exchange, and for connecting subscribers' lines terminating at the manual exchange with such trunk circuit.

In the drawing, a manual exchange X is connected with the automatic exchange Y, 65 by means of a trunk circuit C terminating at exchange X in a dialing or calling jack 1, and a connecting jack 4, and at the automatic exchange in suitable means adapted to select any subscriber's line terminating 70 thereat and to connect the trunk circuit therewith. The apparatus shown at the left of the dotted line 3—3 is located at the manual exchange, while that shown at the right thereof is located at the automatic 75 exchange. The apparatus diagrammatically illustrated at the right of line 3—3 for extending the trunk circuit C to the subscriber's line 2, terminating at the automatic exchange, may be of the type disclosed 80 in Patent No. 1,271,133 granted to H. P. Clausen, July 2, 1918. The tip and ring conductors 29 and 30 respectively of the trunk circuit C may be connected directly to the conductors 29 and 30 respectively of the 85 Clausen patent, disregarding the contact bank at which such leads terminate and all apparatus at the left thereof.

A dialing or calling cord circuit A and a connecting cord circuit B are provided at 90 the manual exchange X for selecting the line at the automatic exchange Y and for connecting a calling subscriber (not shown) with the trunk circuit C respectively. Additional cord circuits similar to the cord circuit B may be provided at the manual exchange for interconnecting the lines terminating thereat; the listening keys of such cord circuits may be connected to the leads 95 6 and 7 extending from the operator's telephone set. Relay 8 controls the association of the operator's telephone set with the cord circuit A through a repeating coil 9, while relay 10 co-operates with the dialing or calling device 11 to render the operator's telephone set ineffective during the calling operation, and relay 32 prevents the contemporaneous association of such set with the cord circuit A and one of the connecting circuits similar to cord circuit B. Relays 14, 100 110

15 and 16 coöperate to control the association of jacks 1 and 4 with the trunk circuit, and control the supervisory lamp 17.

It is thought that the invention may be 5 more fully comprehended from the following description of the operation of the system shown on the drawing:

Assuming that the operator at the exchange X in answering a call received in 10 the usual manner over a suitable line circuit (not shown) terminating thereat, ascertains that a connection is desired with substation 2 on a line terminating at the automatic exchange Y. The insertion of plug 19 into 15 jack 4, operates relay 14 and lights lamp 17 over a circuit established from battery through the lamp 17, the resistance 18, the sleeve contacts of plug 19 and jack 4, the left-hand winding of relay 14, and the contact 20 of relay 15 to ground.

Plug 20 of the dialing or calling cord A, is thereupon inserted into dialing jack 1, thereby operating relays 8 and 16 over a circuit established from battery through the 25 left-hand contact of relay 14, the winding of relay 16, the tip contacts of jack 1 and plug 20 and the winding of relay 8 to ground. The operation of relay 8 connects the operator's telephone set inductively to 30 the ring and sleeve contacts of plug 20 and the jack 1 through the medium of repeating coil 9. The opening of the normal contacts of relay 16 removes the conductors associated with the tip and ring contacts of 35 jack 4 from their normal connection with conductors 29 and 30, respectively, while the closure of the alternate contacts of relay 16 connects the ring and sleeve contacts of jack 1 to the conductors 29 and 30 respectively. 40

The operator actuates the calling or dialing device 11 in the usual manner to connect the trunk circuit C with the line circuit leading to substation 2. The first actuation 45 of the device 11 closes the contact 12 to operate relay 10 over a circuit established from battery through the winding of relay 10 and the contact 12 of the device 11 to the ground. The closure of the alternate contact 50 of relay 10 short-circuits the secondary winding of repeating coil 9, while the opening of the normal contact of such relay opens the circuit including the primary winding of such repeating coil. The contact 12 is closed before the contact 13 is 55 opened, and remains closed until the calling device is restored to normal, at which time relay 10 releases and the operator's telephone set is reassociated with the ring and sleeve conductors of the cord circuit A. 60

The trunk circuit connecting apparatus at the exchange Y operates responsive to the opening and closing of contact 13 of device 11 in the manner described in the Clausen 65 patent as being responsive to the dialing by

the calling subscriber. The reassocation of the operator's telephone set with the cord circuit A upon the restoration of the device 11 to normal when the dialing operation is complete, enables the operator at exchange 70 X to listen for the "busy" tone which, as mentioned in the Clausen patent, will be encountered if the line 2 is busy.

The absence of the "busy" tone notifies the operator at exchange X that the called line 2 is idle, and the plug 20 is thereupon removed from jack 1, thereby disconnecting the ring and sleeve contacts of jack 1 from the conductors 29 and 30, and restoring the tip and ring contacts of jack 4 to their normal association with conductors 29 and 30 respectively. Thereupon a bridge, including the retardation coil 22, the right-hand contact of relay 14, and the winding of relay 15, is connected across the conductors 80 29 and 30. However relay 15 is polarized and does not operate at this time. Upon the answer of the coiled station 2, the connecting apparatus functions in the manner described in the Clausen patent, and the 85 consequent reversal of the battery supply connected to the trunk conductors 29 and 30 causes the operation of the polarized relay 15. The opening of the contact of the relay 15, removes the short circuit formerly 90 established around the right-hand winding of the relay 14, thereby sufficiently increasing the resistance of the circuit, including the supervisory lamp 17, to extinguish such lamp, thereby notifying the operator that 95 the called party has answered. The subsequent removal of plug 19 from jack 4 restores all apparatus to normal.

If while the plug 20 remains in the jack 1, and the calling device 11 is in its normal position, a listening key similar to key 21 connected to the leads 6 and 7 and included in another cord circuit similar to cord circuit B is actuated, relay 32 is operated over a circuit extending from the battery associated with such cord circuit through the lower contacts of the actuated listening key, conductor 6, winding of relay 32, retardation coil 23, conductor 7 and the upper contact of the actuated listening key to the ground. Relay 8 releases due to the short circuit established around the winding thereof, removing the operator's telephone set from association with the cord circuit A, so that the busy tone which might be received over the trunk circuit C is effectively prevented from being transmitted to any subscriber whose line might be connected with the cord circuit associated with the actuated listening key. Also the possibility 110 of any interference caused by the operator receiving such tone while engaged in conversing with such subscriber, is prevented.

It will be evident that in this invention the operator's telephone set, although effec- 125

tive to receive tones incident to establishing connections through the automatic exchange, is rendered ineffective during the actual selecting period, and that any possibility of interference caused by such tones is prevented.

What is claimed is:

1. In a telephone exchange system, a trunk circuit, a link circuit for connection therewith, an operator's telephone set adapted to be connected to the link circuit upon the connection of the link circuit with the trunk circuit, an impulse-sending device connected to the link circuit, and automatic means for disconnecting the operator's telephone set from the link circuit only during the operation of the impulse-sending device. 5
2. In a telephone exchange system, a trunk circuit terminating in a plurality of terminals, a link circuit for connection with one terminal, another link circuit for connection with another terminal, an operator's telephone set, and means jointly controlled by the connection of both link circuits with the trunk circuit for connecting the operator's telephone set with one link circuit. 10
3. In a telephone exchange system, a trunk circuit with normally connected and normally disconnected terminals, link circuits for connection with each terminal, means jointly controlled by the connection of a link circuit with each terminal to connect the normally disconnected terminal to the trunk circuit and to disconnect the other terminal 15
- 35 therefrom, an operator's telephone set, means cooperating with the above mentioned means to connect the operator's telephone set with the trunk circuit, a calling device associated with the link circuit adapted for use with the normally disconnected terminal, and means controlled thereby to disconnect the operator's telephone set from the associated link circuit during the operation of the calling device. 20
4. In a telephone exchange system, a trunk circuit with normally connected and normally disconnected terminals, a link circuit for connection with the normally connected terminal, a second link circuit for connection with the normally disconnected terminal, an operator's telephone set, a repeating coil, means jointly controlled by the connection of the link circuits with the terminals to disconnect the normally connected terminal from the trunk circuit and to connect the normally disconnected terminal thereto, additional means controlled thereby for connecting the operator's telephone set with the second link circuit through the repeating coil, a calling device associated with the second link circuit, and means for short-circuiting the repeating coil winding connected to the link circuit thereby rendering the operator's telephone set ineffective during the operation of the calling device. 25
5. In a telephone exchange system, a trunk circuit with normally connected and normally disconnected terminals, a link circuit for connection with the normally connected terminal, a second link circuit for connection with the normally disconnected terminal, an operator's telephone circuit adapted for association with either link circuit, means jointly controlled by the connection of the link circuits with the trunk circuit to disconnect the normally connected terminal from the trunk circuit and to connect thereto the normally disconnected terminal, additional means controlled thereby for connecting the operator's telephone set with the second link circuit, a calling device for the second link circuit, means for preventing the connection of the operator's telephone set with the second link circuit during the operation of the calling device, and additional means for preventing the contemporaneous association of the telephone set with both link circuits. 30
6. In a telephone exchange system, a trunk circuit for extending a connection from a manual exchange to an automatic exchange, a link circuit at the manual exchange for connection with the trunk circuit, a plurality of terminals for the trunk circuit at the manual exchange, a plurality of link circuits for connection therewith, an operator's telephone set, and means controlled by the connection of a plurality of link circuits with the trunk circuit for operatively associating the operator's telephone set with one of the connected link circuits. 35
7. In a telephone exchange system, a link circuit, an operator's telephone set, means for inductively connecting such operator's telephone set with the link circuit, a second link circuit, means for conductively connecting the operator's telephone set thereto, and means responsive thereto to disconnect the operator's telephone set from the first link circuit. 40

In witness whereof I hereunto subscribe my name this 16th day of January, A. D. 1919.

CLARENCE B. FOWLER.
